UNITED STATES PATENT OFFICE.

OROSCO C. WOOLSON, OF NEW YORK, N. Y.

CLINKER GRINDER AND DISCHARGER FOR FURNACES.

1,121,888.

Specification of Letters Patent. Patented Dec. 22, 1914.

Application filed January 30, 1914. Serial No. 815,351.

To all whom it may concern:

Be it known that I, Orosco C. Woolson, a citizen of the United States, residing in New York city, in the county of New York and State of New York, have invented certain new and useful Improvements in Clinker Grinders and Dischargers for Furnaces, of which the following is a specification.

10 My present invention is a modification of the improvement disclosed in my allowed application, Serial No. 747,004, filed Feb. 8, 1913, and it consists in a modified mode of operating the component members of the 15 clinker grinder and is arranged to manually operate them, independently of their connection with the usual power-driven operating means.

In the drawings, Figure 1 is a broken sectional side elevation, Fig. 2 a front elevation, Fig. 3 a section at 3—3, and Fig. 4 a section at 4—4, Fig. 1. Figs. 5 and 6 are cross sections illustrating different forms of bars for doweling or alining the grinder 25 sections.

This apparatus is a variant (save in its novel features) of the disclosures made in said application, whose reference numerals are used with like significance herein. As 30 in that case, the furnace is constructed with an axial bearer frame F for the grate bars g and therein a front bearing b, a rear bearing b⁴ and intermediate bearings b¹, b², all coaxial, for the tubular grinder, S; with 35 hearth plates and shields, respectively 3 and 27, and a branch flue 30, connecting the bore of the grinder with the chimney flue. The grinder is made up of a front carrier or driver B, a rear carrier C and intermediate 40 helically-toothed grinders or grinding sections D, revolvably mounted in said bearings; operably connected with said grinder is a power drive, comprising a ratchet wheel 8, crank L, and pawl 7; and the grinding 45 sections are operably connected with the driver B by a prismatic bar R in their bore, said bars being preferably a Y or star section, as shown in Figs. 2 to 5 inclusive, although any shape having an engaging edge

will operate satisfactorily, as illustrated in 50 Fig. 6.

The novel constructions are as follows: I simplify the connections of the sections of the grinder S with the bar R. Longitudinal engaging conformations d, are formed 55 in the grinder sections, being preferably internal ribs, as illustrated in Fig. 4; and such conformations engage a margin or margins of the bar R. Said bar is cut to length and confined in the bore of the grinder S between a cross bar or spider 5^b formed in the carrier C, and a transverse pin p inserted in and removable from the driver B.

I adapt the grinder S to be hand-driven independently of the ratchet and pawl 60 drive, by forming a polygonal terminal crank-socket S^o in the exposed end of the driver B, or other suitable arrangement.

I provide effective cooling for the driver B by making in its wall, adjacent to its inward bearing b¹, holes B^o through which it 70 draws air supply which circulates about and prevents excessive temperatures in said driver.

As in said allowed application the grinder 75 S is cooled by a current of air drawn through its bore by the suction of a flue 30 with which it communicates. To prevent heavy particles from clogging said flue, I bed in the rear wall of the furnace an expanding T, 30^a, whose small inner branch 80 is separated by a measurable space from the carrier C, to provide for its expansion, and which is loosely connected therewith by a nipple 30^b driven into said T; whose transverse branch communicates with the flue 30; and whose outward branch expands and is 85 connected, by a nipple 32 and L, 31^d with a sump 31, preferably made of as large a pipe as can be conveniently used. A removable 90 cap 31^b and plug 31^c respectively closing, and opposite to the end of, the sump pipe 31, permit the sump to be periodically cleaned out.

The simple mode of connecting the bar R 95 and grinder S considerably cheapens the first cost and the assembling of the apparatus.

Providing an independent engagement (by means of the ribs d) between the bar R and each grinding section D , renders the device temporarily operable in case one of 5 the cast sections D cracks, or otherwise gives out.

To facilitate removal of the bar R when 10 repairs or replacements are necessary, I provide coaxial with and in the rear of the bore of the grinder a normally plugged opening 30^b through which a rod can be inserted to drive out the bar R or for cleaning 15 the bore of the grinder. In this instance the opening 30^b is shown as formed in the 1, 31⁶.

As described in said allowed application, 20 all the conformations of the sections of the grinder S are such that the grinders D can be inserted or lifted out, when the bar R is not in place.

Having thus described my invention, I claim:

1. In sectional, tubular clinker grinders 25 revolvably mounted beneath furnace fire boxes and comprising engaging tubular end and intermediate grinding sections and a bar extending through and connecting said sections, the combination therewith of engaging conformations on said bar and on each of said grinding sections, said engaging conformations on said bar and grinding sections being spaced from one another to form continuous free passages of air 30 through adjacent sections from one to the other, said end housing sections extending out of the furnace proper so that the aforesaid continuous air passages have inlets and outlets externally of said furnace proper.

2. In sectional, tubular clinker grinders 40 revolvably mounted beneath furnace fire boxes and comprising engaging tubular end and intermediate grinding sections and a bar extending through and connecting said sections, the combination therewith of engaging conformations on said bar and on each of said grinding sections, said engaging conformations on said bar and grinding sections being spaced from one another to form continuous free passages of air 45 through adjacent sections from one to the other, said end housing sections extending out of the furnace proper so that the aforesaid continuous air passages have inlets and outlets externally of said furnace proper, 50 and a crank-engaging conformation at exposed end of the outward section of said grinder.

3. In sectional, tubular clinker grinders 55 revolvably mounted in bearings beneath furnace fire boxes and comprising engaging tubular end and intermediate grinding sections and a bar extending through and connecting said sections, the combination therewith of cooling means comprising perfora-

tions in the wall and between the bearings 60 of the hearth section of said grinder, and a flue connected with the bore of the wall section thereof.

4. In sectional, tubular clinker grinders 70 revolvably mounted in bearings beneath furnace fire boxes and comprising engaging tubular end and intermediate grinding sections and a bar extending through and connecting said sections, the combination therewith of cooling means comprising perforations 75 in the wall and between the bearings of the hearth section of said grinder, a flue connected with the bore of the wall section thereof and a plugged branch of said flue coaxial with and adapted to give access to 80 the rear of said grinder.

5. In combination with a sectional tubular clinker grinder revolvble in bearings beneath a furnace fire box and comprising engaging tubular end and intermediate 85 grinding sections provided with air inlets and connected with a flue, there being a bore throughout said sectional tubular clinker grinder, a sump connected with said bore and flue. 90

6. In combination with a sectional tubular clinker grinder revolvble in bearings beneath a furnace fire box and comprising engaging tubular end and intermediate grinding sections provided with air inlets and 95 connected with a flue, there being a bore throughout said sectional tubular clinker grinder, a T connecting said bore and flue and a sump connected with said T.

7. In combination with a sectional tubular clinker grinder revolvble in bearings beneath a furnace fire box and comprising engaging tubular end and intermediate grinding sections provided with air inlets and connected with a flue, there being a bore 105 throughout said sectional tubular clinker grinder, a fitting connecting said bore and flue, a sump, and an expanding fitting connecting said bore and flue with said sump. 100

8. In combination with a sectional tubular clinker grinder revolvble in bearings beneath a furnace fire box and comprising engaging tubular end and intermediate grinding sections provided with air inlets and connected with a flue, there being a bore 115 throughout said sectional tubular clinker grinder, a fitting connecting said bore and flue, a sump, an expanding fitting connecting said bore and flue with said sump, a removable cap to, and an opposite removable 120 plug in a wall of said sump and a removable plug coaxial with the bore of said grinder.

9. In sectional, clinker grinders revolvably mounted beneath furnace fire boxes and 125 comprising engaging end and intermediate housing sections and a shaft extending through and connecting said sections, the

combination therewith of engaging conformations on said shaft and on each of said grinding sections, said engaging conformations on said shaft and grinding sections being spaced from one another to form continuous free passages of air through adjacent sections from one to the other, said end housing sections extending outside of the furnace proper so that the aforesaid continuous air passages have inlets and outlets externally of said furnace proper.
